(57) **CLAIM**

I claim the ornamental design for a wheel shield for tire detailing, as shown and described.

DESCRIPTION

FIG. 1 is a perspective view of a wheel shield for tire detailing, showing my new design;

FIG. 2 is a top view of a wheel shield for tire detailing, showing the four supports;

FIG. 3 is a bottom view of a wheel shield for tire detailing;

FIG. 4 is a side elevational view of a wheel shield for tire detailing, looking directly at and down one of the supports; and,

FIG. 5 is a side elevational view of a wheel shield for tire detailing, looking directly half way between two of the supports.
